UNITED STATES PATENT OFFICE.

CLINTON S. STONER, OF WEST UNITY, OHIO, ASSIGNOR OF ONE-HALF TO
JAMES H. MILLER AND JOHN A. HOLLINGTON, OF SAME PLACE.

DISPLAY-STAND.

SPECIFICATION forming part of Letters Patent No. 613,609, dated November 1, 1898.

Application filed March 2, 1898. Serial No. 672,327. (No model.)

To all whom it may concern:

Be it known that I, CLINTON S. STONER, a citizen of the United States, residing at West Unity, in the county of Williams and State of Ohio, have invented certain new and useful Improvements in Display-Stands; and I do hereby declare the following to be a full, clear, and exact description of the invention, such as will enable others skilled in the art to 10 which it appertains to make and use the same.

My invention relates to improvements in display-stands more particularly for store or show windows.

It has for its object, among other things, 15 principally to provide greater convenience of access to the displayed goods or articles in the window, the ready convertibility of the table into a series of shelves and, contrariwise, the latter back into a table, and to promote 20 simplicity of construction and lessen parts, and therefore cheapen cost of manufacture.

To these ends the invention consists, primarily, of a convertible table or stand composed of a series of sections adapted to serve 25 in the capacity of shelves and means adapted to support it so as to be readily turned horizontally and of certain other parts combined therewith, substantially as hereinafter more fully disclosed, and specifically pointed out 30 in the claims.

In the accompanying drawings, illustrating the preferred form of carrying out my invention, Figure 1 is a view showing it as a table. Fig. 2 shows it in elevation in the form of a 35 series of shelves. Fig. 3 is a sectional elevation thereof. Fig. 4 is a detailed view of a shelf-bracket. Fig. 5 is a similar view of the retaining device for the table or shelf sections. Fig. 6 is a view of a modification of 40 the hinging or connecting together of the table or shelf sections. Fig. 7 is a modified form of crane or standard for the stand. Fig. 8 is a modification of the table or shelf section retaining device. Fig. 9 is a modification 45 of the shelf or table sections disclosing an ogee form of abutment between them.

Latitude is allowed herein as to details, as they may be changed without departing from the spirit of my invention and the same yet 50 remain intact.

In the embodiment of my invention I con-

struct the table A of a series of sections a a, 55 adapted to form shelves arranged so as to be perfectly flat, with their upper faces flush and each having applied to its sides lateral right-angled brackets B, having their long arms preferably screwed thereto and arranged between lateral bars C, with their short arms connected to corresponding lateral bars C'. The shelves or sections a are also each pivoted at 60 each side, close to one edge, to the lateral bars C, as at B, which pivotal connections may be screws passed through said lateral bars and the long arms of the brackets B. The connection between the lateral bars C' and the short 65 arms of the brackets B may be effected by rivets b' or otherwise. The sections or shelves a themselves are inclined or offset at their normally forward edges, as at a', to slightly lap or overhang each other to limit 70 their movement as they are caused to assume the form of a table and stand flush with each other.

The lateral bars C' may be braced and connected together by rods c, bent or looped into 75 eye-ended projections on said lateral rods, each two rods preferably crossing each other.

The table-sections a when arranged as shelves may be held or guarded as against possible accidental individual movement by 80 means of a tightening screw-threaded and headed rod d, passing through the lateral bars C' and opposite short arms of two of the right-angled brackets B, said rod also passing through a sleeve or tube d', arranged 85 between said lateral bars and provided with a tightening or holding thumb-nut d², preferably having a ratchet bearing-surface. Sandwiched between the head of the rod d and the nut d² and the respective lateral bars 90 C' are ratchet-faced, clamp, or washer-like plates d³, having claw-like ends or flanges overlapping the front edges of said lateral bars and adapted to engage adjacent short arms of the aforesaid right-angled brackets 95 B to prevent the folding of the same, and thus secure the series of table-sections a in their position as shelves.

D is preferably a crane-like standard or support for the stand or table A, in this instance 100 of the form shown in Figs. 1, 2, and 3—i. e., right-angular or crane shape in its general

contour, though tubular in its individual cross-section—with its upper end preferably forming a sleeve e , adapted to receive a pivot e' , depending from a plate or casting e^3 , 5 screwed or otherwise secured to the under side of, say, the middle table-section a , the lower end of said standard being similarly formed, itself, however, being let into a central preferably sleeve-extended aperture in a base disk or plate f , having divergent feet f' . Among other advantages attributable to this 10 construction of standard it may be observed that a series of convertible shelf-sections can be swung into a vertical position and yet be revolved so as to change the angle of presentation—as, for example, in bay windows—without having to bodily manipulate the stand, as would be required in the use of lateral supports as heretofore employed in this 15 class of devices, making this form of standard especially desirable in this connection. It is obvious that it would be impossible for the shelves to assume an upright position if a straight standard were employed.

20 25 In the modification as disclosed in Fig. 6 it will be seen that the pivoting or connecting together of the table-sections a may be effected by dropping the right-angled brackets and employing parallel lateral bars C^2 , 30 connected by pivots, as at C^3 , to each of said sections at diagonally opposite points thereof.

In the modification of Fig. 7 I have shown 35 an arcuate crane-like standard D' , having, preferably, swiveled connection with the stand and foot-piece and suitably fixed at said points of connection by suitable means as may be found expedient.

In the modification as disclosed in Fig. 8 I 40 may employ in lieu of the aforesaid described table or shelf retaining device the suitably sleeved and end-headed or enlarged tightening-rod d^4 and the slotted ratchet-faced link d^5 , with one end pivoted, it may be, upon one 45 of the pivots of a table-section bracket, projecting through a lateral bar C' . The rod d^4 passes through the slot of the ratchet-faced link d^5 and has fitted upon the end thereof, outside of said link, a toothed disk or detent d^6 , adapted to engage the ratchet-face of said 50 link, and swiveled in the embrace of said detent is a thumb-nut d^7 , fitted also upon said rod d^4 to adapt the detent to bear upon said link as the nut is turned, and thus lock the parts firmly together. The swivel connection 55 between said detent and nut may be effected, as herein shown, by providing said detent with opposed arms d^8 , having arcuate terminals d^9 let into a circular recess d^{10} , formed in said nut.

60 With the use of my invention it will be seen that the stand arranged as a table at the first, after having been suitably disposed in the bay or bow window of a store, the goods for display can be conveniently placed thereon, 65 each section having allotted to it the required assortment for exposure. This having been done, the sections a always occupying a hori-

zontal position, they (said sections) are so adjusted with their contents as to form shelves, as in Figs. 2 and 3, after which the stand is 70 swung around to present the goods for exposure or display through the window toward the sidewalk, as required.

When it should be required to empty the stand at any time, it can be readily swung 75 around to bring the goods or articles thereon conveniently to the operator, and thus permit ready access thereto for their removal and the replenishing of the same with others, as may be desired, and the stand again returned to its previous position for the display 80 of the goods or articles.

Having thus fully described my invention, what I claim, and desire to secure by Letters Patent, is—

85 1. The convertible table and display-stand, consisting of the table-sections or shelves, each having right-angled brackets fixed to its sides, the parallel lateral bars, the upper lateral bars pivoted to the normally horizontal 90 arm of each of said brackets, at its inner end, and the lower lateral bars pivoted to the normally vertical arm of each of said brackets at the lower end, the crane-like supporting-standard connected to one of said table-sections or shelves, and axially pivoted in a support, and means for retaining said table-sections or shelves in fixed position, substantially as set forth.

100 2. The convertible table and display-stand consisting of the table or shelf sections each having lateral right-angled brackets, parallel lateral bars, two pivoted to normally horizontal arms of said brackets, and two to normally vertical arms of said brackets, the 105 sleeve-inclosed rod passed through opposite ones of said latter bars, with its sleeve arranged intermediately of said opposite lateral bars, the ratchet-faced clamp having claw-like flanges embracing the edges of said opposite lateral bars and adjoining bracket-arms, a thumb-nut fitted upon the screw-threaded end of said rod and adapted to bear upon said clamp, and a supporting-standard 110 connected to the under side of one of said table or shelf sections, substantially 115 as set forth.

3. The convertible table and display-stand, consisting of the table or shelf sections, the lateral parallel bars, said shelf or table sections having inclined overlapping forward 120 and rear edges and pivotally connected at diagonally opposite points to said lateral bars, and the bail or crane shaped standard connected to the under side of one of said shelf or table sections and axially supported 125 or pivoted in position, substantially as set forth.

In testimony whereof I affix my signature in presence of two witnesses.

CLINTON S. STONER.
